UNITED STATES PATENT OFFICE.

WILLIAM A. SCHLEICHER, OF CLEVELAND, OHIO.

DESIGN FOR A VEHICLE-STEP.

SPECIFICATION forming part of Design No. 21,188, dated December 1, 1891.

Application filed October 30, 1891. Serial No. 410,404. Term of patent 14 years.

To all whom it may concern:

Be it known that I, WILLIAM A. SCHLEICHER, of Cleveland, in the county of Cuyahoga and State of Ohio, have invented a new and original Design for Steps for Vehicles, of which the following is a full, clear, and exact description, reference being had to the accompanying photograph, forming part of this specification, which shows in plan view the surface

or pad of a vehicle-step embodying my design. The design consists of a vehicle-step having a surface configuration substantially as herein described and shown. In the middle of the step-surface or pad is a pattern of rectangu-

lar outline composed of series of adjacent figures. Surrounding this is a plain band, and surrounding the band is a border composed of two rows or series of short outwardly-directed parallel ridges.

I claim—

The design for vehicle-steps, substantially as herein shown and described.

In testimony whereof I have hereunto set my hand this 3d day of October, A. D. 1891.

WILLIAM A. SCHLEICHER.
